UNITED STATES PATENT OFFICE.

JOSEPH THEBAULT, OF CENTRAL FALLS, RHODE ISLAND.

SPINDLE.

1,144,394.

Specification of Letters Patent. Patented June 29, 1915.

Application filed June 16, 1914. Serial No. 845,375.

To all whom it may concern:

Be it known that I, JOSEPH THEBAULT, citizen of the United States, residing at Central Falls, in the county of Providence and State of Rhode Island, have invented 5 new and useful Improvements in Spindles, of which the following is a specification.

My present invention pertains to spindles, and consists in the peculiar and advan- 10 tageous spindle, hereinafter described and claimed, constructed with a view to being mounted in a spinning machine to receive filling yarn and to then be placed in a shuttle and serve the purpose of a spindle in 15 the shuttle, thereby obviating the use of a bobbin and lessening the liability of the inner layers of yarn being injured as generally occurs when a cop is removed from the spindle of a spinning machine and is placed 20 upon the spindle of an ordinary shuttle.

In the accompanying drawings which are hereby made a part hereof; Figure 1 is a view, partly in elevation and partly in section, comprising a spindle constructed in 25 accordance with my invention and a spindle holder adapted to form a permanent part of a spinning machine; it being understood that the said elements may be used in a spinning machine in a horizontal position, 30 in a vertical position or in any other position compatible with the purpose of my invention. Fig. 2 is a view showing my novel spindle as properly positioned and fastened in a shuttle body. Fig. 3 illustrates the relative arrangement of the spindle holder in 35 the shuttle body and the spindle precedent to the securing of the latter in the shuttle body. Fig. 4 is a view of the spindle holder. Fig. 5 is a view illustrating the catches of the 40 holder as engaging the flange of the spindle. Fig. 6 is a cross-section of the spindle, showing the recesses in the flange thereof to receive the said catches.

Similar numerals of reference designate 45 corresponding parts in all of the views of the drawings.

Among other elements, my invention comprises a spindle holder 1, designed to form part of a spinning machine. The said holder 50 is provided with a stem 2, and said stem is designed to fit snugly on the stem 3 of a whirl 4. These parts may be arranged in a horizontal position, as shown or in a vertical position without affecting my invention. In 55 the holder 1 is an inner seat 5 and an outer

seat 6, the outer seat being provided at diametrically opposite points in its side wall with recesses 7 for the reception of the heads of catches 8, the inner ends of the said heads being beveled as indicated by 9 for a purpose presently set forth. 60

The shuttle body 10 for use in carrying out my invention is equipped with a spring backed spindle holder 11 and transverse rods 12 and 13. 65

My novel spindle 14 is provided with a tip 15 of any suitable description, and is gradually diminished in diameter from the said tip to the flange which is arranged at an intermediate point in the length of the 70 spindle, the described taper of the spindle being resorted to in order to enable it to better hold yarn thereon. The flange of the spindle is preferably stepped as shown and comprises a comparatively small portion 16, 75 designed to snugly occupy the inner seat 5 of the holder 1, and a large portion 17 designed to snugly rest in the outer seat 6 of the holder. In the large portion 17 of the stepped flange notches 18 are provided as 80 shown for the reception of the heads of the catches 8 so as to enable the said catches in practice to rest flush with the outer side of the flange portion 17. Extending from the inner side of the flange on the spindle is a 85 spindle portion 19, notched at 20 and 21 to receive the rods 12 and 13, respectively, when the spindle portion 19 is socketed in the holder 11 of the shuttle body and is 90 swung with said holder into the position shown in Fig. 2.

In the practical use of my improvement the spindle while in the holder 1 in a spinning machine is filled with yarn, and the said spindle is then removed from the holder 95 1 and is placed as shown in Fig. 2 in a shuttle body so as to give off yarn in the conventional manner incidental to the movements of the shuttle in a loom.

I prefer to employ the catches 8 for securing the spindle in the holder 1 inasmuch as the said catches are reliable in operation and can be readily moved outwardly to permit of the withdrawal of the spindle from the holder. I do not desire, however, to be understood as confining myself to the employment of the said catches as any other means may be employed for detachably retaining the spindle in the holder and assuring the rotation of the spindle with the 110

holder, without departure from my claimed invention.

Having described my invention, what I claim and desire to secure by Letters-Pat-
5 ent, is:

1. In a detachable connection of a spindle holder and a spindle, the combination of a holder having a seat and a tubular stem or extension, a spindle having a flange con-
10 structed and arranged to occupy said seat and also having a notched portion or ex-
tension arranged to occupy said tubular stem or extension, and means carried by the holder for detachably securing the flange
15 of the spindle in the seat of the holder and causing the holder and spindle to rotate together.
2. In a detachable connection of a spindle

holder and a spindle, the combination of a holder having a seat and notches in the wall 20 of the seat and beveled catches resting in said notches and also having a tubular stem or extension, and a spindle having a flange constructed and arranged to occupy the seat in the holder and peripheral notches in the 25 outer side of said flange to receive the catches on the holder and further having a notched portion or extension arranged to occupy said tubular stem or extension.

In testimony whereof I have hereunto set 30 my hand in presence of two subscribing wit-
nesses.

JOSEPH THEBAULT.
